ALBERT ROSENBOAND, OF NEWARK, NEW JERSEY, ASSIGNOR TO THE ROSENBOAND MANUFACTURING CO., OF NEWARK, NEW JERSEY, A CORPORATION OF NEW JERSEY

CLASP FOR POCKETBOOKS AND THE LIKE

Application filed November 6, 1928. Serial No. 317,576.

The present invention relates, generally, to spring operated fastening clasps for pocketbooks and other devices; and the invention relates, more particularly, to a type of pocketbook clasp comprising two plates hinged together and adapted to receive between them a flap of the pocketbook and to secure the flap by means of a stud carried by one of said plates which stud passes through a hole in the flap. Further the invention relates to a clasp of the kind described in which, when in use, one of the plates is mounted at the back face of a part of the pocketbook and the other plate, hinged thereto, is exposed at the outer face of the same part, with the hinge connection between the two plates extending through an opening made for that purpose in said part of the pocketbook.

Heretofore, in the use of clasps of this kind on pocketbooks the hinge connection between the two plates was not readily detachable and attachable; and, because the two plates could not be attached to each other after the back plate has been put in place within the pocketbook structure, it was necessary to cut a long slit in the material of the pocketbook, at the place of the clasp hinge, to allow the rear plate to be passed to the back face. Such a large slit detracts from the strength of the pocketbook and mars its looks, and has to be sewn up after the clasp has been put in place.

It is an object of the present invention to provide a clasp structure comprising a back plate and a front plate and a disengageable hinge connection, the parts of which latter are carried by one or the other of said plates, preferably unitary therewith, and which can be engaged into hinging relation when the back plate is in place on the back face of a pocketbook part, a comparatively small hole which will be hidden by the front plate being provided for the hinge parts to extend through.

Various other objects and advantages of the invention will be obvious from the following particular description of a form of clasp embodying the invention or from an inspection of the accompanying drawings; and the invention also consists in certain new and useful features of construction and combina-

tions of parts hereinafter set forth and claimed.

In the accompanying drawings there is shown for purposes of illustration one form of apparatus embodying the invention, in which:—

Figure 1 is a partial view of a pocketbook showing a flap thereover held by a clasp of the invention, attached to said pocketbook;

Figure 2 is an enlarged view of the pocketbook at the clasp, and in part broken away;

Figure 3 is a back plan view of the assembled clasp;

Figure 4 is a sectional view taken along the line 4—4 of Figure 1;

Figure 5 is a front face view of the pocketbook part to which the clasp is attached, showing the opening at which the latter is attached and showing the back plate of the clasp in dotted lines and a connecting part, broken off from the front plate, as it is being attached to the back plate;

Figure 6 is a back plan view of the two plates of the clasp at an intermediate step during attachment of the two plates together;

Figures 7 and 8 are perspective views, respectively, of the back plate and front plate.

Throughout all views of the drawing like reference characters are employed to indicate corresponding parts.

Referring now to the drawings, the reference character 1 indicates a metal back plate for a clasp having formed therein a longitudinal opening 2 adjacent which near one end, one on each side, are a pair of openings 3, 3. The strips of metal between said openings 3, 3 and opening 2 are punched to form a pair of loops 4, 4 which stand out on the front face of said back plate 1 and which are separated from each other by said opening 2. In line with said opening 2 and near the opposite end of said back plate 1 is secured a riveted stud 5 which projects outwardly on the front face of back plate 1. Said stud 5 is adapted to extend through the perforated pocketbook flap which is to be received by the clasp of the invention. Said stud 5 carries a flange or shoulder 6 which seats against the front face of the back plate 1, and on the back

face of back plate 1 said stud 5, under its riveted end, carries a flat spring 7 which normally extends over said opening 2 and which can be moved rotatably on said stud 5 into positions into and out of alignment with said opening 2. At its outer end said flat spring 7 is reversely curved to form a projection 8 facing toward said back plate 1 and adapted to engage and press against an eccentric member on a cooperating front plate hereinafter fully described.

A front plate 9 which cooperates with said back plate 1 is flat and has its outer end rounded off and curved outwardly to provide a finger hold for opening the clasp. At its opposite end said front plate 9 is turned at right angles for a short portion 10 from which projects centrally a tongue 11 whose width is slightly less than that of said opening 2 and which has a pair of ears 12, 12 which extend oppositely in the plane of said tongue 11, and an eccentric lug 13 which extends centrally from said tongue 11 and is offset backwardly, that is, in a direction away from the outer end of said front plate 9.

Said plates 1 and 9 are assembled together by turning said flat spring 7 from over said opening 2, inserting said lug 13 and ears 12, 12 through said opening 2 from the front face of back plate 1, and turning said plates 1 and 9 with respect to each other to bring said ears 12, 12 into said loops 4, 4 with the outer end of said plate 9 extending toward said stud 5. With said front plate 9 opened away from said back plate 1 on their hinged connection, to bring said eccentric lug 13 into said opening 2, said flat spring 7 is turned into a position over said opening 2 and left in that position. In this position of the parts whenever said front plate 9 is opened or closed, from or to said back plate 1, said eccentric lug 13 will engage said projection 8 on spring 7 and the closing or opening movement will be against the pressure of said spring 7 and the terminating movement in either direction will be with a sharp snap as the eccentric lug 13 moves past the dead center of said projection 8 with respect to the hinged connection of said ears 12, 12 with said loops 4, 4. And said spring 7 will firmly hold said front plate 9 in the closed position over or against said stud 5.

The back and front plates 1 and 9 are assembled on a pocketbook, for example, in a manner similar to that above described, as follows. A pocketbook 14 having a front portion 15 over which folds a flap 16 is provided with a small, oblique opening 17 at a point adjacent to the position of the outer edge of said flap 16 when the latter is closed or folded over said front portion 15. An opening 18 is provided to receive said stud 5 at a position under said flap 16. Said back plate 1 is placed with its front face against the back face of said front portion 14, with

said opening 2 in registry with said opening 17 and with stud 5 extending through opening 18. The front plate 9 is then assembled on said back plate 1 in hinged relation, in the manner above described, said eccentric lug 13 and ears 12, 12 being inserted through said opening 17 and then through said opening 2. The said opening 17 is made oblique because said ears 12, 12 and lug 13 are turned at an angle to be inserted through said opening 2, and opening 17 being so made, obliquely, is of a minimum size. The said flat spring 7 is turned to lock the two plates 1 and 9 together. A patch 18' of cloth or leather or other suitable material if desired, can be sewed or glued to the back face of said front portion 14, over said back plate 1, to keep the latter in place and to keep the said stud 5 from coming out of said opening 18, or a lining of the pocketbook will serve this function, or said back plate 1 can be stitched in place on said front portion 14. Said flap 16 is provided with an opening 19, in which is fastened an eyelet 20, to receive said stud 5 when said flap 16 is closed over the pocketbook and inserted under said front plate 1, which latter will be closed over it to keep it in place, locked on said stud 5.

While I have shown and described a clasp with a stud 5 for extending through an opening in a pocketbook flap, the clasp can be used to have the front plate 9 extend through a loop or slit in the pocketbook flap in which case said stud 5 can be used as a stop for said front plate 9 and other obvious changes can be made in the arrangement of the parts.

Having thus described my invention, what I claim is:

1. In combination, in a pocketbook clasp, a back plate arranged to be positioned within a pocketbook, said back plate having an opening rearwardly of an opening in the body portion of the pocketbook, and aligned loops formed one on each side of said back plate opening; a front plate arranged to be positioned exteriorly of a pocketbook and having an offset tongue extending through the pocketbook opening and through said opening in the back plate, the front plate having a pair of aligned, laterally extending ears, each engaging in a respective one of said loops and forming therewithin a pivotal connection; said tongue being extended in an eccentric lug extending backwardly from said loops; and a stud riveted to said back plate and extending from the front face thereof through a conforming aperture in the body portion of the pocketbook toward said front plate for engagement in an eyelet provided in the flap of the pocketbook; and a flat pressure spring mounted on said riveted stud rearwardly of said back plate and extending into pressure applying contact with said eccentric lug, said pressure spring overlying said back plate opening and being turnably mounted on said stud, whereby said spring

may be turned from said opening for inserting or removing off-set tongue.

2. In combination, in a pocketbook clasp, a front plate having a forward portion mounted exteriorly of a pocketbook, said front plate having a tongue extending rearwardly at substantially a right angle from the forward portion thereof, a pair of aligned ears extending laterally from said tongue, and an eccentric lug extending beyond said ears; a back plate for mounting within a pocketbook, said back plate having a longitudinal opening therein in alignment with an opening in the body portion of the pocketbook, said back plate and said pocketbook openings being of a length to admit said ears therethrough, said back plate opening being of a width slightly greater than the width of said tongue, said back plate having struck therein oppositely positioned and aligned loops, one on each side of said back plate opening, said loops being adapted to receive said ears in pivotal relation, a stud extending through said back plate secured thereto, said stud projecting forwardly through an opening in the body portion of said pocketbook toward said front plate for cooperation with an eyelet provided in the flap of the pocketbook, a pressure spring turnably mounted upon said stud rearwardly of said back plate and having a portion overlying said back plate opening and engaging said eccentric lug rearwardly of said back plate, said pressure spring being turnable about said stud away from said back plate opening to admit said eccentric lug and said ears through said opening.

3. In combination, in a pocket book clasp, a front plate having a forward portion positioned forwardly of a pocketbook and having a tongue extending rearwardly at substantially a right angle from said body portion, a pair of aligned ears extending laterally from said tongue, and an eccentric lug extending beyond said ears; a back plate arranged to be positioned behind said front plate and within a pocketbook, said back plate having a longitudinal opening therein, rearwardly of an opening in the body of the pocketbook, said back plate opening being of a length to admit said ears therethrough and of a width slightly greater than the width of said tongue; said back plate having struck therein oppositely positioned and aligned loops, one on each side of said opening, adapted to receive said ears in pivotal relation; a stud secured to said back plate and extending forwardly therefrom through an opening in the body portion of said pocketbook toward said front plate for cooperating with an eyelet of the flap of said pocketbook; and a flat pressure spring rotatably mounted on said stud at the rear of said back plate and having a portion thereof extending in pressure applying contact with said eccentric lug, said pressure

spring overlying said back plate opening and being turnable away from said opening to admit said off-set tongue therethrough.

In testimony, that I claim the invention set forth above I have hereunto set my hand this 29th day of October, 1928. 70

ALBERT ROSEN BAND.
